UNITED STATES PATENT OFFICE

ALBERT S. VELCHEK, OF SOUTH CHICAGO, ILLINOIS

DESIGN FOR A COASTER

Application filed June 21, 1929. Serial No. 31,781. Term of patent 14 years.

To all whom it may concern:

Be it known that I, ALBERT S. VELCHEK, a citizen of the United States, and a resident of South Chicago, in the county of Cook and State of Illinois, have invented a new, original, and ornamental Design for a Coaster, of which the following is a specification, reference being had to the accompanying drawing, forming part thereof.

I claim:

The ornamental design for a coaster, as shown.

Signed at Chicago, in the county of Cook and State of Illinois, this 14th day of June, A. D. 1929.

ALBERT S. VELCHEK.
